TOY CATAPOULTING GUN

Charles G. Hall, Los Angeles, Calif., assignor of
one-half to Louis V. Dieter, Los Angeles, Calif.

Application November 7, 1950, Serial No. 194,462

2 Claims. (Cl. 124—17)

1

This invention relates to toy catapulting guns, which can be used for throwing balls, arrows, toy aeroplanes and other objects forwardly or upwardly with considerable force and to some distance.

Among the salient objects of the invention are: to provide a toy gun of the character referred to which is simple and economical in construction and which is practical and efficient in function; to provide in such a toy gun means whereby either balls or arrows or other objects can be catapulted therefrom without the necessity of many different attachments, or many changes to adapt it for different articles to be thrown or catapulted forwardly or into the air.

In order to explain my invention more in detail, I have illustrated one practical embodiment thereon on the accompanying sheet of drawings in which:

Figure 1 is a side elevation of a toy catapulting gun embodying my invention;

Figure 2 is a fragmentary, enlarged sectional view thereof, to show more of the construction and arrangement of the operating parts;

Figure 3 is an enlarged cross sectional view, taken on line 3—3, of Fig. 2;

Figure 4 is a fragmentary sectional view taken on line 4—4 of Fig. 2;

Figure 5 is a plan view looking down on the catapulting device and showing the handle for pulling it back to a setting position;

Figure 6 is a fragmentary side elevation showing an arrow in said catapulting device, with the ball-receiving cup removed;

Figure 7 is a fragmentary view showing how a parachute with rod can be inserted in said catapulting device, while

Fig. 7A shows said parachute in opened condition after having been catapulted into the air; and

Figure 8 is a fragmentary side view showing how a toy aeroplane can be mounted on said catapulting device to be shot into the air.

Referring now in detail to the drawings, my toy catapulting gun as here shown for explanatory purposes, includes a handle portion 10, having a barrel 11, secured thereto and having its top formed as an open slot for the greater portion of its length, as at 11', the outer end thereof being closed and having a coiled spring 12 secured therein, as shown in Fig. 2, to serve as an abutment for the catapulting device, to be described later.

Also included in said barrel is an endless rubber band 13, one end of which is placed around

5 a collar 14, held by a pin 14' in the end of said barrel, as seen in Fig. 2, and the other end of which is secured to a through pin 15, through a tubular portion 16 of a catapulting device which includes a neck or web portion 17 which extends through the open slot in the top of the barrel 11, as will be seen in the sectional view in Fig. 4, with a tubular portion 18 on the top edge of said web portion, and on which tubular portion 18 is a U-shaped member or portion 19, as will be understood from the showing in Figs. 2 and 4. The web portion and the tubular portions 16 and 18 connected thereto, and the U-shaped member 19, are sufficiently elongated as 10 to give bearing in the barrel, as seen in Fig. 2. A T-handle is shown secured to the rearward end of the neck or web 17, said handle being designated 17' and by means of which the catapulting device can be pulled, against the tension of 15 the rubber band 13. The underside of the tubular portion 16, in the barrel 11, is provided with a slot 16' to receive the upturned end or toe 20' on the end of a straight spring member 20 secured in the handle 10, as seen in the sectional view in Fig. 2. This forms a latch toe to spring 20 into said slot 16' for the purpose of holding the catapulting device rearwardly in its set position, as seen in Fig. 2. The straight spring member 25 is secured at its rear end by screws, as 21. A trigger member 22 is secured to the toe end of 30 said latch spring 20, as shown, and this is operated for moving the latch toe 20' out of the slot 16' to release said catapulting device, to be thrust forwardly by the rubber band, until it strikes the 35 spring 12 in the outer end of the barrel, as clearly shown. The rearward end of the tubular portion, in the barrel 11, is tapered, as at 16a to pass over the toe 20'.

It will be understood that the catapulting device can be used for throwing different objects 40 forwardly or into the air. In Figs. 1, 2 and 4, a cup 23, having a shank 24, is anchored in the forward end of the U-shaped member 19, as shown, with a removable cotter pin 25 therethrough for holding it in place. This cup can be used for throwing balls or other objects which 45 can be placed therein, as indicated.

In Fig. 6, an arrow 26 is shown in place in the tubular portion 18, which is closed at its rearward end to force said arrow forwardly as said catapulting device is released in the manner before described.

In Fig. 7, a toy parachute 27 is in place, with 55 its stem 27' inserted in said tubular portion 18,

as indicated, ready to be catapulted into the air, to open and descend as indicated in Fig. 7A.

In Fig. 8, I have shown how a toy aeroplane, as 28, can be mounted in the U-shaped member 19, by removing the cup 23 from said U-shaped member. A shoulder, as at 28' on said aeroplane bears against the forward end of said member 19, as clearly indicated in Fig. 8.

Thus I have provided a simple, practical and economical toy catapulting gun having a catapulting device operable thereon capable of holding balls, arrows and other objects to be catapulted, and while I have shown and described one practical embodiment of the invention, I do not limit the invention to the details of construction and arrangement shown for purposes of explanation, except as I may be limited by the here-to appended claims.

I claim:

1. A toy catapulting gun, as shown, having a 20 handle portion and a barrel secured thereto and having its top formed as an open slot for the greater portion of its length, the outer end thereof being closed and having a coiled spring secured therein to serve as an abutment for the catapulting device, an elastic rubber extended through said barrel and through said coiled spring and secured in the outer end of said barrel, a tubular guide portion in the opposite end of said barrel and to which said elastic rubber is attached for pulling it through said barrel, said tubular guide portion having a web portion extended through the open slot in the top of said barrel and provided on its upper edge with an article-holding member to receive articles to be catapulted therefrom as said member is forced with said tubular guide portion and said web portion through said barrel and its open slot to the outer end of said barrel, and a trigger-operated latch element for holding said tubular guide portion and said article-holding member in the rear end of said barrel with said elastic rubber under tension for discharge.

2. A toy catapulting gun including a handle portion and a single barrel secured thereto and having its top formed as an open slot for the greater portion of its length, the outer end of said barrel having said slot closed, a coiled spring in the outer end of said barrel and anchored at its outer end in the outer end of said barrel, a tubular guide member in said barrel and movable back and forth therein, said member having a web portion extending up through said open slot in the top of said barrel and having connected therewith an article-holding member to move along the top of said barrel as said tubular guide member moves within said barrel and said web portion moves through said open slot in the top of said barrel, and a tension member within said barrel and secured at one end to said tubular guide member and at its other end anchored in the outer end of said barrel, whereby when said tubular guide member is pulled to the rear end of said barrel said tension member is put under tension, and a trigger-operated latch member for releasably holding said tubular guide member under tension in the rear of said barrel to be released for catapulting action.

CHARLES G. HALL.
